BY
Walter B. Burrow

ATTORNEY.

UNITED STATES PATENT OFFICE.

WILLIAM H. BOZE, OF NORFOLK, VIRGINIA.

COLLAPSIBLE STAND.

1,340,370.

Specification of Letters Patent. Patented May 18, 1920.

Application filed December 29, 1919. Serial No. 348,083.

To all whom it may concern:

Be it known that I, WILLIAM H. BOZE, a citizen of the United States, residing at Norfolk, in the county of Norfolk and State 5 of Virginia, have invented certain new and useful Improvements in Collapsible Stands, of which the following is a specification.

My invention relates to collapsible or foldable stands.

10 The object of the invention is to provide a foldable stand for tables, drawing boards, washboards and the like so that it may be folded and hung on the wall or against the wall with the edges resting on the floor 15 when not in use and when required for use may be quickly extended so as to act as a support for boards to form a table.

A further object is to construct a stand 20 or support that may be cheaply constructed 20 and be adjustable both transversely and longitudinally.

Further objects and advantages will be 25 more fully described herein and specifically pointed out in the annexed claims 25 recourse being had to the accompanying drawing forming a part of this specification in which:—

Figure 1 is a perspective view of my 30 device in position to receive a board or boards to form a table.

Fig. 2 is a plan of the same, and Fig. 3 35 is a plan of two of the transverse members of the support showing means for effecting lateral adjustability.

35 In the drawings like reference numerals indicate similar parts in all the several views:—

1 are the supports which consist of two 40 crossed members intersecting at the center to form X-shaped standards.

2 are the lower brace bars inserted near the lower ends of the X-shaped supports for rigidity and for the lower ends of the hereinafter described vertical rods.

45 3 are the top upper cross bars provided with channel ways 4 for the slidably mounting of the transverse adjusting bars 5 and 6.

The bars 5 and 6 are provided with slots 6^a through which pass the bolt 7, and by 50 means of the winged nut 8, the bars may be slidably extended outward to get the greatest width or retracted to make the space narrower according to the width of

the board or boards which are to rest upon them.

55 The bars 5 and 6 are provided with pins 9 which pass through suitable holes in the board to be supported by the stand in order to prevent it from slipping off said bars, or if preferred, the holes may be made in 60 the bars 5 and 6 to receive pins placed in the board to be supported, as desired.

11 are vertical rods passing through the intersection of the crossed or X-shaped supports 1 and the lower cross bar 2 and may 65 be extended above the bars 5 and 6, as shown by dotted lines 12, Fig. 1, in which case the projecting ends thereof will answer the purpose of the pins 9.

13 and 14 are slidable rods for effecting 70 longitudinal adjustment and are disposed one upon the other and held at the proper point by means of the clamp collar or sleeve 15 through which passes the bolt and winged nut 16 thereby binding the two rods and 75 holding them in position.

By loosening the nut 16 the rods may be pulled outward to lengthen or pushed inward to shorten and afterward clamped so that they will remain at any position de- 80 sired.

By having longitudinal and transverse adjustment the stand is adapted to support drawing boards, ironing boards, table boards and the like which are of different 85 width and lengths so that the stand may serve for several purposes, as described.

The rods 13 and 14 are provided with ring ends or eyes 17 through which passes the vertical rods 11 and are therefore hing- 90 edly fitted and adapted to turn upon said vertical rods.

18 are angle brace rods provided with ring ends or eyes 19 and are likewise encircling the vertical rods 11 so that they 95 may turn thereon.

20 is a sleeve or collar provided with a suitable set screw so that it may be slidably adjustable on the rod 13 and also upon the rod 14 but one only is shown in Fig. 2. 100

21, Fig. 2, shown by dotted lines, represents the position taken by a board or boards to form a table or for a drawing or ironing board. As shown, the rods 11 turn in the eyes of the rods 13 and 14 so 105 that the device may be collapsed or folded

in the position shown by the dotted lines in Fig. 1.

As the device is plainly shown in the drawing further description is deemed unnecessary.

5 I claim:

1. A device of the class described and in combination with supporting standards, 10 grooved upper members thereon, transversely adjustable slotted members slidably mounted in the grooved members, friction clamps therefor, vertical rods passing through said supporting standards, and longitudinally adjustable slidable rods 15 hingedly connected to said vertical rods.

2. A device of the class described and in combination with supports or standards, 20 transverse adjustable members thereon, vertical rods passing through said supports, adjustable and slidable longitudinal rods, hingedly secured to said vertical rods, clamp securing means for said slidable rods, and adjustably mounted on said slidable

rods for causing the rods and supports to close one upon the other.

3. A device of the class described and in combination with supports or standards, 25 of transversely adjustable members thereon, vertical rods through said supports and projecting above said upper transverse members and secured at one of their ends near the lower ends of the supports, longitudinal ring ended rods adapted to slide one over the other for adjustment, diagonal brace rods having ring ends or eyes 30 thereon connecting said vertical rods with the longitudinal rods for causing said transverse members to hingedly turn upon said vertical rods.

In testimony whereof I have hereunto affixed my signature in the presence of two witnesses.

WILLIAM H. BOZE.

Witnesses:

STELLA L. BOZE,

WALTER B. BURROWS.
